COMBINED LABEL HOLDER AND PULL

Roy A. Stone, Rockford, Ill., assignor to National Lock Co., Rockford, Ill., a corporation of Delaware

Filed Nov. 12, 1964, Ser. No. 82,571

Term of patent 14 years

(Cl. D10—8)

FIG. 1 is a front elevational view of a combined label holder and pull embodying my new design;

FIG. 2 is a rear elevational view thereof;

FIG. 3 is a top plan view thereof;

FIG. 4 is a bottom plan view thereof;

FIG. 5 is an end elevational view of one end thereof;

FIG. 6 is an end elevational view of the other end thereof; and

FIG. 7 is a sectional view on the line 7—7 of FIG. 1

I claim:

The ornamental design for a combined label holder and pull, substantially as shown.
